DEVICE FOR TENSIONING METAL BINDING
STRIPS FOR PACKAGES AND THE LIKEOscar Kind, Rodenkirchen, near Cologne,
GermanyApplication May 21, 1937, Serial No. 144,101
In Germany March 20, 1937

2 Claims. (Cl. 254—76)

This invention relates to devices for tensioning metal binding strips for packages and the like and in particular to a device of this type which can be used in combination with one of the many common devices which serve to produce the fastening for such bindings produced with a wire or flat strip and the subject of the application relates to the known tensioning devices used for such purposes, in which the tensioning of the strips is effected by means of two automatic clamping devices which can alternately be moved towards each other and away from each other through the actuation of a hand lever and which act on the end of the strip to be tensioned in such a way that they allow the strip to pass freely into the tensioning device between the clamping surfaces whilst retaining it in the opposite direction.

In the previously known tensioning devices of this kind one of the two tensioning clamps is fixedly disposed so that it only serves as a stop clamp for retaining the strip during the return movement of the second clamp actuated by the hand lever. The hand lever must thus make a free stroke between each tensioning stroke, in order to bring the movable clamp again into the operative position.

Contrary to this, in the subject of the application, both tensioning clamps are movably disposed and are connected with the hand lever in such a way that they are moved towards each other on swinging the hand lever in one direction and away from each other on moving the hand lever in the other direction. In this way one of the two tensioning clamps acts to advance the strip each time in the direction of the tensioning, whilst the other clamp moves backwards from the direction of tensioning. By utilizing in this way both strokes of the tensioning lever to promote the tensioning a considerable saving in time is effected. Moreover, this method of operation simplifies the diminution of the separate tensioning strokes and thus effects a corresponding increase in the number of tensioning stages. In this way it is easier for the operator to effect alterations in the tensioning force produced than if larger tensioning stages were used, separated by pauses for free strokes. The invention thus not only enables each separate binding to be more quickly effected but also makes possible a more uniform and accurate regulation of the peripheral tension of the separate bindings.

Reference will now be made to the accompanying drawings which illustrate one form of

construction of the tensioning device according to the invention in which:

Fig. 1 shows by way of example the tensioning device in combination with a twisting device, in front elevation, as generally used in a similar way for the production of wire bindings,

Fig. 2 shows a corresponding plan view,

Fig. 3 shows on a larger scale the essential parts of the tensioning device itself in front elevation,

Fig. 4 is a sectional elevation on the line IV—IV of Fig. 3,

Fig. 5 is a vertical section on the line V—V of Fig. 3,

Fig. 6 illustrates schematically the method of operation of the device.

The common base plate 1 of the tensioning and fastening device, which is placed on the package to be bound up, carries in the centre part of its front edge the fastening device which is operated by swinging the fastening handle 2 backwards and forwards in conjunction with the toothed wheels 3 and two twisting pinions 4. On the left side of the twisting device there is provided a clamping eccentric 5, serving to retain one end of the binding strip 35 (Fig. 6) at the level of the axle of the twisting pinions 4 and which is disposed in such a way that in the known manner it can be operated, by means of its hand lever 6, about a horizontal axis above the supporting surface 1.

On the opposite side of the fastening device the tensioning device is disposed on a guiding block 8 united with the base plate 1 on whose front vertical surface parallel to the edge of the base plate and the axis of the twisting pinions there are disposed two longitudinally displaceable slides 10, 11 between the two parallel guiding members 9. The slides are provided with thrust arms 12, 13 which are so arranged that they overlap each other in the space between the slides. The thrust arms are provided with pin holes 14, 15 which are extended vertically to a certain extent and in which two crank-pins 16, 17 penetrate, the latter being provided on the plate shaped end part 18 of the horizontal tensioning lever axle 19. This lever axle rests in a bearing 20 lying on the rear side of the guiding block 8 and carries at its rear end the tensioning lever 21. By the oscillation of the latter from left to right and vice versa the two slides 10 and 11 can therefore be moved simultaneously in opposite directions and alternately to and from each other by means of the two crank pins 16, 17.

On the front surface of each of the two slides

10, 11 between each pair of retaining members 22 guiding their edges, there is provided a horizontally projecting carrying pin 23 on which rests a holding plate 24 which is fixed against rotation 5 by means of projections 25 thereon engaging in slots 26 of the respective slide body. Each plate 24 carries at its lower edge a horizontally projecting plate 27 which acts as a buttress for the clamping action of the eccentric pawl 28 which is 10 rotatably disposed in front of the holding plate 24 on the carrying pin 23. The two eccentric pawls are somewhat longer than the distance between the axis of the carrying pin and the surface of the buttress plate 27. They are both obliquely disposed with the same inclination towards the right so that they can both swing out in the direction of the tensioning movement away from the fastening device whilst the opposite movement is limited by contact with the anvil 15 plate.

In front of the eccentric pawls 28 a lift part 29 is provided on each of the two carrying pins 23 so that an angle member 20 thereof overlies the upper end surface of the eccentric pawl 28 so that 25 this lift part 29 must also make the oscillating movements of the eccentric pawl 28. The lift part is provided at its rectangular end edge with a forwardly projecting lifting arm 31, whose lower end 32 projects slightly beyond the rectangular 30 edge of the buttress plate 27. The front edge of this lifting arm is constructed as a backwardly and downwardly inclined cam surface 33 which projects to such an extent that, with the counter-pressure of the end of the wire or strip 35 of 35 the binding to be tensioned, by the action of this oblique surface the lift part 29 together with the eccentric pawl 28 is raised towards the right and the clamp is thereby opened, so that the end of the binding wire on the other side of the 40 pointed end 32 of the lifting arm 31 can enter between the buttress plate 27 and the end of the eccentric pawl 28 and be fixed by this. In front of the lift part 29 a helical spring 34 is provided on the front end of the carrying pin 23 in such a 45 way that through its outer free end the lift part 29 and accordingly the eccentric pawl 28 is pressed downwards against the buttress plate 27. While the binding wire can raise the lift part 29 by the cam action induced by the engagement of 50 said wire with the cam surface 33, it is obvious that this same cam action does not occur once the wire is inside or rearwardly of the part 29. The hook-shaped end of part 29 operates to prevent the part 29 from being raised by the wire and 55 the part 29 thereby constitutes a keeper to retain the wire in position on the buttress plate 27.

When operating the device the extreme end of the binding wire 35, as can be seen from Fig. 6, is drawn in between the clamp eccentric 5 and its 60 supporting surface 7 by operation of the hand lever 6. After guiding the binding wire 36 around the package and guiding back its tensioning end 37 the latter is placed on the edges of the buttress plates 27 laterally in front of the cam surface 33 of the two clamping devices and is 65 pressed against the lifting arm 31 so that it rises and the end of the wire drops in between the buttress plate and the eccentric pawl which has thus been raised.

70 If the hand lever 21 is then swung outwards in the direction of the arrow 38 the two slides 10, 11 will then be drawn towards each other in the direction of the arrows 39. In this way the clamp

on the left side takes along the wire clamped between its eccentric pawl and its buttress plate in the direction of the tensioning movement, whilst the eccentric pawl conveys the other clamp freely over the wire which has thus been drawn forwards. In the opposite swinging movement of the lever the two clamps move away from each other, the clamp on the right side acting in the direction of the tensioning whilst the left hand clamp makes its free stroke. 10

It is apparent from the foregoing that the device has a double action and that tightening is achieved irrespective of the direction in which the lever 21 is swung.

Instead of being used with wires the device 15 can obviously be used for tensioning more or less broad iron binding strips, by means of a suitable widening of the eccentric pawls. Naturally in this case other auxiliary means must be used instead of a twisting device in order to effect the 20 mechanical union of the two overlapping ends of the strip.

I claim:

1. In a tie tensioning device including a stationary gripping member for gripping one bight 25 of said tie and movable gripping means for gripping the opposite bight of said tie; said movable means comprising a pair of reciprocal gripping members each of which is adapted to grip and tension said second bight when said member is 30 moved in one direction and to release said second bight when moved in the opposite direction, a rock shaft, means for rocking said shaft, one end face of said shaft being disposed adjacent both of said gripping members, diametrically opposed 35 crank pins on said end face of said shaft, integral extensions of said gripping members, and each of said pins being operatively connected to one of said extensions whereby rocking of said shaft in one direction moves one of said gripping members in a gripping direction and rocking of said shaft in the opposite direction moves the other gripping member in the gripping direction. 40

2. In a tie tensioning device including a stationary gripping member for gripping one bight 45 of said tie and movable gripping means for gripping the opposite bight of said tie; said movable means comprising a pair of reciprocal gripping members each of which is adapted to grip and tension said second bight when said member is 50 moved in one direction and to release said second bight when moved in the opposite direction, a rock shaft, means for rocking said shaft, one end face of said shaft being disposed adjacent both of said gripping members, diametrically opposed 55 crank pins on said end face of said shaft, integral extensions of said gripping members, and each of said pins being operatively connected to one of said extensions whereby rocking of said shaft in one direction moves one of said gripping members in a gripping direction and rocking of said shaft in the opposite direction moves the other gripping member in the gripping direction.

3. In a tie tensioning device including a stationary gripping member for gripping one bight of said tie and movable gripping means for gripping the opposite bight of said tie; said movable means comprising a pair of reciprocal gripping members each of which is adapted to grip and tension said second bight when said member is moved in one direction and to release said second bight when moved in the opposite direction, a rock shaft, means for rocking said shaft, one end face of said shaft being disposed adjacent both of said gripping members, diametrically opposed crank pins on said end face of said shaft, integral extensions of said gripping members, and each of said pins being operatively connected to one of said extensions whereby rocking of said shaft in one direction moves one of said gripping members in a gripping direction and rocking of said shaft in the opposite direction moves the other gripping member in the gripping direction, and a movable keeper pivotally connected to each of said movable gripping members, each of said keepers comprising an outer cam surface engageable with said second bight and thereby effective to raise said keeper and permit the positioning of said bight beneath said gripping member, said keeper including means for thereafter maintaining said bight beneath said gripping member. 60

4. In a tie tensioning device including a stationary gripping member for gripping one bight of said tie and movable gripping means for gripping the opposite bight of said tie; said movable means comprising a pair of reciprocal gripping members each of which is adapted to grip and tension said second bight when said member is moved in one direction and to release said second bight when moved in the opposite direction, a rock shaft, means for rocking said shaft, one end face of said shaft being disposed adjacent both of said gripping members, diametrically opposed crank pins on said end face of said shaft, integral extensions of said gripping members, and each of said pins being operatively connected to one of said extensions whereby rocking of said shaft in one direction moves one of said gripping members in a gripping direction and rocking of said shaft in the opposite direction moves the other gripping member in the gripping direction, and a movable keeper pivotally connected to each of said movable gripping members, each of said keepers comprising an outer cam surface engageable with said second bight and thereby effective to raise said keeper and permit the positioning of said bight beneath said gripping member, said keeper including means for thereafter maintaining said bight beneath said gripping member. 65
